US00D997096S

(12) **United States Design Patent** (10) **Patent No.:** **US D997,096 S**
(45) **Date of Patent:** **** Aug. 29, 2023**

(54) **DOCKING STATION FOR MOVING DEVICE**

(71) Applicants: **UBTECH NORTH AMERICA RESEARCH AND DEVELOPMENT CENTER CORP**, Pasadena, CA (US); **UBTECH ROBOTICS CORP LTD**, Shenzhen (CN)

(72) Inventors: **Zhi Heng Leow**, Sherman Oaks, CA (US); **Francisco Jose Hernandez**, Long Beach, CA (US); **Chengkun Zhang**, Temple City, CA (US); **Huan Tan**, Pasadena, CA (US)

(73) Assignees: **UBTECH NORTH AMERICA RESEARCH AND DEVELOPMENT CENTER CORP**, Pasadena, CA (US); **UBTECH ROBOTICS CORP LTD**, Shenzhen (CN)

(**) Term: **15 Years**

(21) Appl. No.: **29/796,558**

(22) Filed: **Jun. 25, 2021**

(51) **LOC (14) Cl.** **13-02**

(52) **U.S. Cl.**

USPC **D13/108**

(57) **CLAIM**

The ornamental design for a docking station for moving device, as shown and described.

DESCRIPTION

FIG. 1 is a first perspective view of a docking station for moving device showing the claimed design in accordance with the present disclosure;

FIG. 2 is a second perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the Figures are for the purpose of illustrating portions of the article that form no part of the claimed design.

1 Claim, 8 Drawing Sheets
